UNITED STATES PATENT OFFICE.

PATRICK J. O'HANLON AND EDWARD A. SMITH, OF PHILADELPHIA, PENNSYLVANIA.

DESIGN FOR AN INKSTAND.

Application filed April 26, 1926. Serial No. 17,462. Term of patent 3½ years.

To all whom it may concern:

Be it known that we, PATRICK J. O'HANLON and EDWARD A. SMITH, citizens of the United States, residing in the city and county of Philadelphia, State of Pennsylvania, have invented a new, original, and ornamental Design for Inkstands, of which the following is a specification, reference being had to the accompanying drawing, forming part thereof.

Figure 1 is a plan view of an ornamental inkstand showing our new design.

Figure 2 is a front elevation of Figure 1.

We claim:—

The ornamental design for an inkstand, as shown.

PATRICK J. O'HANLON.
EDWARD A. SMITH.
